CONCEALED GARMENT FASTENER

Benjamin Berlin and Isidor Herman,
New York, N. Y.

Application August 3, 1934, Serial No. 738,343

2 Claims. (Cl. 2—234)

This invention relates to a concealed garment fastener and has for an object to utilize a continuous separable fastening device as a garment fastener in such a manner that the fastener itself will be entirely concealed and normally invisible when in operation, the fastener being preferably of the type such as described, for instance in United States Letters Patent No. 1,219,881, or of any similar fastener along the 10 general idea disclosed in this particular Letters Patent.

A further object of this invention is to provide a concealed garment fastener which may be utilized in any type of garment such as trousers, 15 sweaters, slip-over sweaters, or other garments wherein it is desirable that a secure and neat fastener be used, yet that the fastener itself be invisible from the outside and furthermore be protected on the inside so that metallic parts cannot 20 come into contact with any part of the body of the wearer even though the garment in which this particular fastener is attached is worn next to the skin.

A further object of this invention is to so construct the garment containing the fastener that the fastener will not only be invisible, but when the garment is pressed the construction of the fastener will not protrude or show a line crease through the garment.

Still a further object of this invention is to apply this invention particularly to the fly of a pair of trousers wherein the metallic part of the fastener as well as the stringers on which the metallic parts are fastened are entirely concealed and invisible even though the flap itself may accidentally be raised somewhat.

With the foregoing and other objects in view, as will hereinafter become apparent, this invention comprises the constructions, combinations and 40 arrangements of parts, hereinafter set forth, disclosed and shown on the accompanying drawings. In these drawings,

Figure 1 is a front elevation of the upper portion of a pair of trousers embodying the invention.

Figure 2 is a view similar to Figure 1 showing the separable fastener flap partially opened.

Figure 3 is a sectional view taken on the line 3—3 of Figure 1.

Figure 4 is a front elevation of a sweater embodying the invention.

Figure 5 is a sectional view taken on the line 5—5 of Figure 4, and

Figure 6 is a view similar to Figure 4 showing

another form of sweater embodying the invention.

There is shown at 10 a pair of trousers to which this invention has been applied. This pair of trousers 10 includes the right leg section 11 and the left leg section 12, the fastener as used in this invention being intended to be part of the fly connecting the portion 11 and the portion 12.

The end of the right leg portion 11 is folded back on itself forming a hem or underlapping flap 14. The stringer 15 of the fastener is laid next to the hem 14 and a covering flap 16 of material folded back on itself is laid over the back of the stringer 15. The ensemble is then stitched 15 together as at 17.

As shown, the flap 16 is a folded over piece of material and when made in this fashion is necessarily entirely of the same material as the trousers, although it will be obvious that the rear portion of section 16 may instead be a piece of lining material, inasmuch as this section will never be visible from the outside of the trousers under any condition.

The other stringer 18 of the fastener member is 25 laid next to a folded over portion or strip of trouser material 19 having the same thickness as the hem portion 14 of the other leg. It will be noted that the underlapping flap and an edge of the strip are in substantially abutting relationship. 30 The edged portion or overlapping flap 20 of the left leg section 12 is then laid next to the folded over portion 19, and the stringer 18 goes over portion 19, then the stringer 18, folded over portion 19 and edged portion 20 are stitched together 35 as at 21. The edged portion 20 of the left leg portion 12 is then sewed as at 22 forming a fly or flap of a sufficient size to entirely conceal the fastener and reach over beyond the stitching 17 on the other leg portion 11.

The metallic portions 23 and 24 of the fastener are of a thickness substantially no greater than the thickness of the stringer portions 15 and 18 to which they are secured, and hence, when the slider 24 has been drawn upwardly securing 45 the fastener together the leg portions 11 and 12 are held in substantially the same plane, the fly portion 20 projecting thereabove in the normal manner.

Due to the presence of the folded over portion of trouser material 19 the metallic elements 24 of the fastener secured to stringer 18 are entirely concealed therebehind, and in the same manner the metallic elements 23 secured to the stringer 14 are likewise concealed behind the edge 55

of the hem 14. There is thus the same thickness of material in front of and in back of each of the stringers and of the metallic elements, and accordingly when the trousers are pressed the 5 fastener is entirely concealed and no crease line is formed which would make the fastener visible therethrough.

Due to the presence of the rear flap 16 it is impossible for any portion of the human body to 10 be accidentally injured by the operation of the fastener. In Figures 4 and 5 this invisible garment fastener is shown as utilized in the coat type of sweater, shown at 25. In applying the fastener to this sweater 25, a hem 26 and 27 is formed 15 on each side of the longitudinal opening of the sweater.

One stringer 15 is laid next to the hem 26 and the other stringer 18 is laid next to the hem 27, the metallic elements 23 being secured to 20 stringer 15 and 24 to stringer 18. The stringer 18 is then sewed to the hem 27 as at 28, but a folded over flap portion 30 of sweater material is laid back of the stringer 15 and then the hem 26, stringer 15, and folded over flap 30 are secured 25 together by stitching 31.

With the fastener utilized in this manner, the folded over flap 30 of sweater material secured to 30 the back of stringer 15 and hem 26, lies over the back of stringer 18 against the back of hem 27 and serves to prevent any contact between the metallic elements of other portions of the fastener and the body of the wearer, while the hems 26 and 27 serve to conceal the stringers and metallic elements from view of the observer.

35 In Figure 6 this same invention has been applied in a manner just described to the sweater 35 which is of the slip-over type, the fastener 36 in this form extending but a short way down from the neck 37. In the coat type of fastener 25 it will be understood that any conventional manner of allowing the lower edge of the fastener to 40 be separated may be utilized.

The novel features and the operation of this 45 device will be apparent from the foregoing description. While the device has been shown and the structure described in detail, it is obvious that this is not to be considered limited to the exact form disclosed and that changes may be

made therein within the scope of what is claimed without departing from the spirit of the invention.

Having thus set forth and disclosed the nature of this invention, what is claimed is:

5 1. In a garment, an invisible fastening means for said garment, the latter having overlapping and underlapping flaps defining an opening, a strip of garment material secured to said overlapping flap, said last mentioned flap overlying the front of the fastening means, said fastening means including a fastener of the continuous type utilizing a pair of stringers, a series of metallic elements secured to each of said stringers, a slider means for connecting and disconnecting said series of metallic elements, one of said stringers secured to said strip of garment material, the second stringer secured to the other flap, and a covering flap secured to said second stringer and overlying the back of the fastener, an edge of the underlapping flap and an edge of said strip being substantially in abutting relationship, whereby to provide a garment capable of receiving a neat pressing with the stringers lying in a single plane and the 10 overlying flap lying flat closely adjacent thereto without bulging.

2. In a garment, an invisible fastening means for said garment, the latter having overlapping and underlapping flaps, each of said flaps characterized by a hemmed fold, a folded strip of garment material secured to said overlapping flap, said last mentioned flap overlying the front of the fastening means, said fastening means including a fastener of the continuous type utilizing a pair of stringers, a series of metallic elements secured to each of said stringers, a slider means for connecting and disconnecting said series of metallic elements, one of said stringers secured to said strip of garment material, the second stringer secured to the other flap, and a folded covering flap secured to said second stringer and overlying the back of the fastener, an edge of the underlapping flap and an edge of said strip being substantially in abutting relationship.

30 35 40 45 BENJAMIN BERLIN.
ISIDOR HERMAN.
